ART OF RATING CYCLIC MOTIONS

Walter Kohlhagen, Elgin, Ill., assignor to Elgin National Watch Company, Elgin, Ill., a corporation of Illinois

Application April 15, 1942, Serial No. 439,128

23 Claims. (Cl. 73—6)

This invention relates to the rating of cyclic motions, and is concerned with methods and apparatus by which such determinations may be conveniently and accurately made.

A feature of the invention is the determination of the rate of oscillating movements of devices which have a plurality of parts so that a cycle of movement produces a succession of impulses, and includes selection among such impulses so that a like point of each cycle is used for comparison.

Another feature is the coordination of starting and rating instrumentalities so that the rating system is released concurrently with the selection of a starting point for the oscillating movement itself.

A further feature is the employment of loading and firing means responsive to individual phenomena of cyclic groups, together with means for selectively employing the same for starting the rating at a predetermined point of a cycle and thereafter effecting a comparison of the time spacing between like points in successive cycles.

A particular feature of the invention, when employed for determining the rate of cyclically oscillating structures such as watch movements, is the inclusion of means for storing energy in the structure whereby it may enter its oscillation, together with a control of the initiation of testing concurrently with the release of the structure for performance of its oscillating movements.

With these and other features as objects in view, as will appear from the following description and the drawings, an illustrative form of practicing the invention is set forth in the drawings, in which:

Figure 1 is a general view of the embodiment of the invention with a perspective showing of certain mechanical structures.

Figure 1a is a conventionalized circuit diagram of electrical parts employed with the mechanical structures of Figure 1.

Figure 2 is a longitudinal axial view through the mechanical supporting structure utilized with a watch balance.

Figure 3 is a sectional view showing a control and air driving means for maintaining the oscillation of the balance.

Figure 4 is a diagrammatic view indicating the relation of the light beam to spokes of a balance wheel while quiescent at the neutral axis.

Figures 5, 6 and 7 are graphs illustrating the balance movement and the relative time positions of current impulses.

The invention is illustratively shown as employed in determining the rate of a standard type

of balance assembly which has two spokes and which oscillates through a total angle of greater than 360 degrees in actual employment.

In Figure 1, a general frame is conventionally shown as a supporting member 10 having structures for supporting the several mechanical parts in proper relationship to one another, and for permitting their required relative movements. A bearing 11 supports a hollow flange 12 of a disk 13 which has an eccentrically extending pin 14 provided at its end with pincers 15 for engaging the end of the hair spring HS of a balance illustrated as having the usual pin P, the balance wheel BW, and the staff S. One end of this staff (at the left in Figs. 1 and 2) is rotatably received in an appropriate cavity in the end of a supporting member 16 which extends coaxially through the disk 13 and is provided with a collar 17 which limits its movement toward the right in Figure 2 under the urging of a spring 18. The supporting member 16 is provided at its end with a knob 19 by which the operator may retract the same for engaging or releasing a balance.

The other end of the balance is similarly received in a cavity at the end of the supporting member 23 which is rotatably mounted in a bearing 24 and is provided at its opposite end with a pinion 25. Adjacent the balance, the supporting member 23 carries a disk 26 which is secured to turn with the member 23 and is provided with a slideable plunger 27 which is mounted eccentrically to the common axis of the supporting members 16, 23 at a proper distance for entering one of the spaces in the balance wheel BW (Fig. 3), so that it can engage with one of the spokes thereof. The plunger 27 is retracted (toward the right in Fig. 1) by the action of a solenoid 30 illustrated as mounted upon the disk 26, and is projected by a spring 28.

As shown in Fig. 1, a source of illumination SL includes an electric lamp 32 and a lens system 33, with an enclosing housing to prevent escape of light except through a diaphragm 34. Mirrors 35, 36, 37 serve to deflect the light so that it passes through the balance wheel BW at a point between its hub and rim, whereby this light beam is interrupted each time a spoke of the balance wheel BW cuts across its path. The light beam from the source SL is thus guided and controlled, and enters the housing EL containing a photoelectric cell PE, and energizes this cell selectively in accordance with its own control by the action of the spokes of the balance wheel BW.

A shaft 40 is supported on the base 10 by a bear-

ing 41 and has a crank 42 by which it may be rocked. The shaft supports a sector rack 43 having teeth engaged with the pinion 25 so that the supporting member 23 can be turned through an angle by actuating the crank 42. An electrical contact 45 is illustrated as carried by the sector arm 43 for selective engagement at the limits of its rocking movement with contacts 46, 47, which are insulatedly mounted on the general frame 10. The contacts 46, 47 are illustrated as adjustable screw elements so that their effective positions can be changed for determining the end positions of the rock shaft 40, and thus of the member 23.

The support 10 also receives a housing 50 to which air may be supplied under pressure through a pipe 51, and which has a nozzle 52 with its orifice adjacent the rim of the balance wheel BW. As shown in Fig. 3, this housing 50 has a slide valve 151 movable therein by a spring 153 and by the armature 154 of an electromagnetic coil 111 connected to conductors 110 and 112. The valve 151 has the groove 152 which, upon energization of the coil 111, is brought into alignment with the ports of the supply line 51 and the nozzle 52, so that a puff of air is then blown through the nozzle under controlled conditions, as described in my co-pending application, Serial No. 443,997, filed May 21, 1942.

As conventionally shown in the circuit diagram portions of Fig. 1a, the photoelectric cell PE is so connected that upon illumination thereof, current will flow through an amplifier 60 for supplying several control devices, the connection of the cell PE and the number of stages in the amplifier 60 being arranged to provide positive voltage with increasing light, in the illustrated form.

For simplicity in the diagram, the cathodes of the various tubes are conventionalized as having heaters adjacent thereto, and an expert in the art will understand that any appropriate means may be employed for exciting the cathodes.

The amplifier 60 is connected to the counting circuits and devices, which include a potentiometer 61 and two electron tubes 65, 66 of the gas-conduction or Thyratron type. The cathodes of the two tubes are connected by a resistor 67, and the cathode of tube 66 is connected through a resistor 68 to a conductor 69 which may be regarded as a ground or reference-potential conductor. The grid of the tube 65 is connected to the potentiometer 61 through a condenser 72, and to the conductor 69 through a grid return resistor 70. The tube 66 likewise has a resistor 74 in its grid return circuit, and is connected through a condenser 72a with the potentiometer 61. The tube 66 has its anode connected through appropriate dropping resistors 79a, 79b to a conductor 75 which leads to the positive terminal of a steady source A of plate current. The anode of tube 65 is connected by conductor 76 to a contact 2 of the starting relay SR, with a return from the corresponding relay switch blade 1 by conductor 77 and an appropriate resistor 78a to the resistor 79b. Condensers 78, 79 are connected between the anodes of the respective tubes 65, 66 and the reference-potential conductor 69, so that they are in effect connected in series between the tube anodes, and also provide in association with the individually corresponding plate resistors 78a, 79a a pair of control devices for effecting the alternate action of the tubes 65, 66 so that these tubes alternately load and fire for the successive impulses from the photocell PE. The presence of the resistor 67 in the individual part of the cathode path of the tube 65, so that it acts to reduce

the current flow through the common resistor 68 while the tube 65 is conducting, as compared with the flow therethrough while the tube 66 is conducting, permits delivering current impulses at different voltage levels as the tubes alternately fire.

From the cathode of tube 66, a conductor 80 with a series condenser 80a and control resistor 80b therein leads to the grid of a third electron tube 81, likewise of gas conduction type and is effective for delivering the said impulses established from the alternate action of the tubes 65, 66, as set out hereinafter; a branched grid return conductor including a resistance 82 and a biasing source 82a leads to the reference-potential conductor 69 for controlling the grid charge in this tube to hold the tube normally in non-conductive condition. The anode of tube 81 is connected through resistor 83 with the source A. The cathode of the tube 81 is connected through a resistor 86 to the reference-potential conductor 69 and thus to the negative side of the steady source A, to provide a positive impulse to the indicating device Q, when tube 81 conducts. A condenser 89 is connected between the negative end of resistor 86 and the anode of the tube and, in association with the resistor 83, provides an RC network as a timing device for controlling the tube 81, which is quickly discharged upon receiving a sufficiently high positive impulse but requires a predetermined time of recharging before it can again respond by discharging. This time is adjusted to be greater than the time elapsing between points b and f (Figs. 5 and 6), and will be described more in detail hereinafter. The source A maintains steady voltages on tubes 65, 66 and 81, and the output voltage from tube 66 is very constant while it is passing current; and hence it will activate tube 81 only when the plate voltage of this tube has reached a certain value by this recharging of the RC network, and thus the tube 81 will be maintained inoperative until the normal time interval from b to f has been exceeded.

The time necessary for condenser 89 to recharge is determined by the value of condenser 89 (for example, 0.5 microfarad) and the series resistor 83 (for example, 400,000 ohms) with a selected supply voltage (for example, 300 volts).

From the cathode of tube 81 leads an output conductor 90 which includes a series condenser 90a and which may be connected to any desired type of indicator Q, being illustratively conventionalized as an oscilloscope with associated time-base circuit. A return conductor 91 leads from the device Q to the reference-potential conductor 69.

The normal or proper motion of the balance does not vary through wide limits. For example, if the period varied plus or minus 72 minutes per day, this would only be a variation of 5 percent. The period can therefore be considered essentially constant within such limits. It is desired to maintain the motion swing of the balance at 1½ turns which is approximately that utilized by the balance in a watch. Regardless of whether a balance swings 1½ turns, 1 turn, or 2 turns (overbank condition), the overall time taken for a complete cycle is approximately the same within very close limits, whereas the change in amplitude of motion may vary 33 percent (1½ to 2 turns). Thus, in order to swing through greater angular distance in the same time, the angular rate must increase. Conversely, decreased motion will cause a decreased angular

rate. Since the light spot covers a fixed angle, preferably made equal to the spoke width for the style of wheel being tested, the time required to scan this spot is less for high amplitudes and greater for low amplitudes. The time required for any one impulse, due to the spoke intercepting the light, depends largely on the total swing of the balance, and in fact, when the wheel is at correct time, the impulse time varies inversely with the motion.

A safety device is provided for assuring that the system will only be made ready and released for operation when the balance wheel has been accurately set with a spoke lying in the neutral axis for intercepting the light which normally falls on the photoelectric cell, and for preventing operation of the machine if this condition is not met. This safety device also assures that the winding pin or plunger 27 will only move forward when the balance spoke is properly in position to prevent contact by the winding pin; and to prevent forward movement of the winding pin or plunger 27 while the balance is oscillating.

For this purpose, the exciter lamp 32 is energized from an alternating current source, through a transformer 141 and a rectifier 140, with the inclusion of an electrical filter circuit comprising the input choke coil 142, a further choke coil 143 and the smoothing condensers 144, along with a steady bleeder resistor 145. This filter, however, is so constructed and designed that it permits a ripple of alternating current to pass to the exciter lamp of such an intensity that on the one hand the ripple has no effect upon the normal operation of the tubes 65, 66, but on the other hand is of such value that upon further amplification and rectification it can provide a voltage for determining the operation of the winding solenoid 30.

A starter relay SR has the energizing coil 121 and two contact blades. In the de-energized condition of the coil 121, the contact blade 122 normally closes a circuit between terminals 1, 2 for the conductors 76, 77. The contact blade 123 normally closes a circuit between contacts 3, 4.

A control relay CR has an energizing coil 125 for moving the normally closed contact blade 126 and thereby opening a circuit between terminals 1, 8.

When the crank arm 42 is in the position shown in Fig. 1, contact 45 is engaged with contact 47 corresponding to the "vibrate" position. In this condition, current is taken by conductor 127 from a part of the steady source A and passes through coil 125 of the control relay CR, and thence to contact 47, through contact 45, and back through the conductor 69 to the source A: control relay CR is energized, and its contacts 7, 8 are open so that the coil 121 of the starter relay SR is de-energized, wherewith contacts 3, 4 are closed and the solenoid 30 is energized and holds the plunger 27 retracted. When the crank arm 42 is moved toward the opposite position, contact 45 leaves contact 47 and current no longer flows through coil 125, so that the relay CR is de-energized, and its contacts 7, 8 are closed and thus prepare the plate circuit of tube 155 by a path leading from the anode of tube 155 through coil 121 of relay SR by conductor 130, contacts 7, 8 through the contact blade 126 of relay CR, with a return to conductor 75 and the steady source A, this steady source also being connected by conductor 69 and through resistances 157, 158 with the cathode of tube 155. It will be noted that the tube 155 is still held biased by resistors 157, 158, so that no

current passes through this tube. Hence coil 121 continues de-energized, and current flows as before through contacts 3, 4 and maintains energization of the solenoid 30, with retraction of the plunger 27. When the crank arm 42 has been moved until contact 45 engages contact 46 in the "wind" position, the resistor 157 is short circuited, whereby the tube 155 may become conductive, provided that the voltage across resistor 252 does not impose a negative potential at the grid of tube 155 exceeding the firing potential of this tube; that is, a control can be exercised from tube 146 upon the tube 155 independently of the position of the crank arm 42. When conditions established through tube 146 and by the contact 45 concur, the tube 155 fires and current then flows through the anode path which has been tentatively established through contacts 7, 8 of relay CR, as set out above, and therewith the solenoid 121 of the relay SR is energized, the contact blade 123 is attracted, and contact points 3, 4 are opened so that current can no longer flow through conductor 128 to the solenoid 30. Hence the solenoid 30 is de-energized and plunger 27 is released to move into its position (Fig. 2) under the action of spring 28, so that it can now engage the balance wheel spoke upon a further movement of crank arm 42.

The coil 121 of relay SR is connected by conductor 130 to terminal 7 of the blade 126 of control relay CR; and terminal 8 of relay CR is connected to conductor 75, so that energizing current may flow from the source A to the coil 121 and thus supply anode current to the control tube system, when the control relay CR is de-energized.

The conductor 95 is employed to control the amplifier tube 146 which has a diode section, this conductor 95 being connected to one end of a potentiometer 147 which is connected at its other terminal to the reference-potential conductor 69. The variable tap of the potentiometer 147 is connected to the grid of the tube 146. The cathode of this tube 146 is connected through a cathode resistor 148, with a by-pass condenser 149, to the conductor 69. The anode of the tube 146 is connected through a resistor 250 with the conductor 75 connected to the positive terminal of the steady source A. A condenser 251 is connected between the main anode and the diode anode of the tube 146, and a further connection is established from the diode anode through a resistor 252 to the conductor 69, and also through resistor 253 to the grid of the gas discharge tube 155. The grid of the tube 155 is connected through condenser 254 to conductor 69.

The gas discharge tube 155 has its cathode connected through the series resistors 156, 157 with the reference-potential conductor 69. The anode of the tube 155 is connected to the coil 121 of a starting relay SR. A resistor 159 is connected between the cathode of the tube 155 and the positive conductor 75. The conductor 131 from the "wind" contact 46 is connected to the common central connection of the resistors 156, 157, so that resistor 157 is short-circuited when the lever is in the "wind" position.

Thus, while the balance wheel is being mounted, if light passes from the exciter lamp 32 to the photoelectric cell PE, this cell is energized, and the ripple effect appears across the potentiometer 147 and the tube 146 delivers a negative voltage effect from its diode. The circuits of tube 155 are so designed, by employment of proper values of the resistors, that the tube 155

remains in the non-conductive state because of the resistors 156, 157 in the cathode circuit. The resistor 159 is connected in series with resistors 156, 157, and causes current to flow therethrough and thus sets up sufficient voltage to keep the tube 155 in a normally non-conductive state, since the cathode of this tube is at a relatively positive potential with respect to conductor 69, and the grid is maintained negative by the amount determined by the current flow through resistors 159, 156, 157. The resistors 156, 157 are so proportioned that when resistor 157 is short-circuited, the bias established by resistor 156 will be just sufficient to permit the tube 155 to fire. This short-circuiting is accomplished by moving the control crank 42 into the "wind" position.

When light falls upon the photoelectric cell PE, the negative voltage at the diode of tube 146 is impressed upon the grid of tube 155, and can maintain this tube against firing, even if resistor 157 is short-circuited. When the spoke of the balance wheel BW is in the neutral axis, however, the light is cut off from the photoelectric cell PE, and the delivery of negative voltage from the diode of tube 146 ceases, so that the tube 155 is permitted to fire, thus delivering current for activating energizing coil 121 of the relay SR.

The resistors 252, 253 also provide with the condenser 254 an RC filter for smoothing out voltage fluctuations which appear across the rectifier, and operates as a timing circuit for determining the rate of drop of the negative voltage derived from the diode of tube 146. Thus, if the balance wheel is oscillating as a result of preliminary mechanical adjustment, the drop of the negative voltage across the condenser 254 is so slow that the grid of tube 155 is not afforded opportunity to permit firing of this tube prior to the time at which the next light impulse encounters the photoelectric cell PE. Hence, the spoke must be essentially quiescent and at the neutral axis before the tube 155 can fire.

Before describing the operation of the parts, it may be pointed out that the path of the light beam LB (Figs. 1 and 4) is fixed, and it is preferable so to adjust the condenser lenses and diaphragm structures 33, 34 that the transverse dimension of this beam corresponds to the width of the spokes of the balance wheel BW at the point of interception, as this gives an optimum accuracy and amplitude of response. Each time a spoke of the balance wheel BW intercepts the light beam LB, the photoelectric cell PE is shadowed. Thus, if the balance wheel BW, which is illustrated as having the usual two diametrically opposed spokes, is rocked through an arc of less than 180 degrees in each direction from a neutral axis NA (Fig. 4), only the lower spoke intercepts the beam, and there is one obscuring effect at each stroke, or two for a complete cycle of movement for the balance wheel BW. If the balance wheel is rocking in each direction through an arc greater than 180 degrees and less than 360 degrees, then both spokes intercept the beam at 180 degree intervals of movement for a total of six obscuring effects per cycle. Since the balance wheel BW is moving fastest when it crosses the neutral axis at the mid-point of each oscillatory stroke, the shadow cast at this event is briefer in duration than that which is cast by the other spoke at 180 degrees displacement before and after the said interception at maximum speed.

In current practice with watch escapements, 75

the balance swings through an arc greater than 180 degrees and less than 360 degrees in each direction from the neutral axis. Since the rate of the oscillatory system may vary slightly when the balance swings through angles less than those employed in actual practice, it is desirable to determine the rate at substantially the same amplitude of oscillation as is performed by the balance while in service.

The successive interceptions may be represented diagrammatically as in Fig. 5, where a curve 160 represents the rocking movement of the balance wheel BW and is conventionally shown as sinusoidal, although it will be understood that departures from strict sinusoidal condition are not unusual, usually by change of the slopes representing the forward or "tick" stroke or the rearward or "tock" stroke relative to one another. For accurate maintenance of time by the balance wheel, it is only necessary that the time interval from cycle to cycle between successive moments at which the balance wheel operates to release the train in a "tick" movement or in a "tock" movement shall be constant, and the time spacing from the "tick" release to the "tock" release need not be the same as that from the "tock" release to the "tick" release. Since a preferred construction is to have the balance release the timing train at the moment of maximum velocity of the balance, this release normally occurs both for the "tick" and the "tock" movements substantially at the neutral axis NA.

If the movement of the balance wheel BW is followed along the curve 160 of Fig. 5, beginning with the balance wheel at a point 161 at which it has been displaced from the neutral axis NA through an angle greater than 270 degrees but less than 360 degrees, it will be noted that the balance wheel gradually picks up speed or accelerates. A spoke (the upper spoke in Fig. 4 after the winding through 330 degrees for example) crosses the light beam LB during this acceleration at a point 180 degrees from the neutral axis and causes a first electric impulse a. The balance wheel continues its acceleration under the urgency of the hair spring and at the neutral axis, a second impulse b of much shorter duration is produced by the interception of the other spoke (the lower in Fig. 4). Thereafter, during this "tick" stroke, the balance wheel BW slows down or decelerates as it is now engaged in winding the hair spring, so that when the upper spoke (of Fig. 4) next passes the light beam LB, a longer impulse c is again produced at 180 degrees from the neutral axis. Ultimately, the balance wheel BW comes to a standstill at a maximum amplitude around 330 degrees, and then returns in the "tock" stroke. In a watch or like movement, the pressure from the timing train adds to the energy of the balance wheel system so that the frictional and other losses are substantially compensated during each cycle and stroke. In the present device, energy is supplied from the maintaining device 50 for a like purpose.

After leaving the point 162 of maximum amplitude at the end of the "tick" stroke, the balance wheel BW begins to move backward under the urgency of the power stored in the hair spring, and during the course of its acceleration, the upper spoke again intercepts the light beam LB at substantially 180 degrees from the neutral axis to give an impulse d of relatively long duration; and then, as the balance wheel continues to accelerate, the lower spoke intercepts the light

beam LB at the neutral axis and at maximum velocity to provide a short impulse *e*. As before, the balance wheel BW now decelerates, and a final long impulse *f* in the "tock" stroke is given by the upper spoke at 180 degrees after the neutral axis; finally the balance wheel BW comes to a standstill at a maximum amplitude of movement represented by the point 163 at the end of the "tock" stroke; and a "tick" stroke begins the next cycle. These "tick" and "tock" strokes alternate, and each pair constitutes a cycle of movement of the balance.

It may further be pointed out that the dotted-line curve 164 in Fig. 5 represents a movement of the balance wheel BW which is in synchronism with the movement represented by the curve 160, but in which the balance wheel is moving through a smaller amplitude or lesser angles (being only slightly greater than 180 degrees). The slopes of the flanks of the curve 164 are much lower than those of the curve 160, and the upper spoke which intercepts the light beam LB at 180 degrees from the neutral axis is moving much more slowly than described above, so that the impulses *f*' and *a*' are much longer than the corresponding impulses *f* and *a* for the curve 160. Furthermore, in Fig. 6, the impulses *a*, *b*, *c* . . . are indicated in their time relationship to one another corresponding to the curve 160, and it will be noted that these individual impulses have short durations corresponding to definite basic frequencies. The triplet groups of impulses are substantially spaced apart because a large part of the total time in each cycle is consumed in slowing down, reversing and returning during the part the angular movement which is more than 180 degrees from the neutral axis, in either direction. However, when the amplitude of movement decreases, a lesser proportion of the time is consumed in these portions of the cycle, so that the successive impulses (Fig. 7) with the curve 164 are individually of greater time duration, and they are farther apart within the triplets, and the end members *c*, *d* and *f*, *a* of adjacent triplets are much closer together: in particular, with an amplitude of 180 degrees, the impulses will coincide.

In operation, the crank handle 42 is initially in the "vibrate" position, (as shown in Fig. 1) i. e. with contact 45 engaged with contact 47. Power is supplied to the electrical circuits and to the lamp 32, and compressed air to the pipe 51. The knob 19 is withdrawn and a balance is inserted into the support 23, and then the knob 19 is released again, so that the balance is now supported for free rocking movement upon the members 16, 23. It will be noted that this is accomplished without any particular orientation of the balance. The hair spring HS is then clamped in the pincers 15 at a point of its length which is believed to represent the proper length of hair spring for accurate timing, the balance rotating about its axis as necessary for this adjustment. The disk 13 is then turned about its axis until one spoke of the balance wheel (the lower spoke in the illustrative form, Fig. 4) intercepts the light beam LB while the balance wheel BW is at rest; this operation establishes the balance at the predetermined neutral axis NA (Figs. 4 and 5). During these adjustments, the balance is turned slowly, and soon comes to rest in the desired initial position.

With the crank handle 42 and the sector 43 in the "vibrate" position for the insertion and orientation of the balance wheel, the contact 45 engages the contact 47; the control relay CR is ener-

gized and current also flows between terminals 3, 4 of the starter relay SR for energizing the winding solenoid 30 so that the plunger pin 27 is held in its right-hand or retracted position in Figs. 1 and 2, and does not interfere with the manipulations of inserting and orienting the balance wheel. Current also can flow between terminals 1, 2 of the starter relay SR, so that the anode circuit of tube 65 is closed.

10 The operator now shifts the crank 42 in a clockwise direction (Fig. 1) from the "vibrate" toward the "wind" position, so that the sector rack 43 drives pinion 25 and turns the disk 26 counter-clockwise through an angle established by the spacing of the contacts 46, 47 in this illustrative form. The plunger or winding pin 27 is held retracted, so that the disk 26 turns independently of the balance wheel BW, the latter remaining essentially without movement. This disk 26 and the winding pin 27 are turned (counter-clockwise or in the direction of the arrow in Fig. 3) through an angle between 360 and 450 degrees. By the original location of the winding pin 27 relative to the spokes of the balance wheel BW, this preferably results in bringing the winding pin 27 to rest, when the contact 45 engages the contact 46 in the "wind" position with the winding pin 27 in an angular position midway between the spokes or at 90 degrees to the neutral axis, so that the pin 27 can move outward or toward the left in Fig. 2 without encountering a spoke of the balance wheel BW. When the contact 45 engages contact 46, further movement of the disk 26 is prevented, and also an electrical circuit is set up through the short-circuiting of resistance 157 so that the tube 155 passes current and energizes the coil 121 of the relay SR.

40 Energization of the relay SR causes the system to establish the conditions necessary for initiation of the testing operation. Opening of contacts 3, 4 causes de-energization of the winding solenoid 30 so that the winding pin 27 moves outward or toward the left in Fig. 2. Contacts 1, 2 of relay SR are opened so that the tube 65 ceases to receive any plate current and hence tube 66 is caused to fire and to continue to pass current.

45 The operator now shifts the crank 42 backward in a counter-clockwise direction (Fig. 1) from the "wind" to the "vibrate" position, so that the sector rack 43 drives the pinion 25 and the disk 26 is turned clockwise through the aforesaid angle as established by the spacing of the contacts 46, 47. When the contact 45 leaves the contact 46, the resistor 157 is no longer short-circuited, but the tube 155 continues to pass current and to hold the coil 121 of relay SR energized, thus preventing false operation in the event of multiple partial movements of the crank 42 or in the event of chatter at the contacts 45, 46. The winding pin 27 during the mechanical movement ultimately engages a spoke of the balance wheel BW and turns the balance in a clockwise direction (Fig. 1) so that this balance is displaced against torsion of the hair spring through an angle in excess of 270 degrees, this angle preferably being adjusted to be about 330 degrees, but insufficient to cause a spoke to twice pass the beam of light. Thus, it is normally preferred to have the winding pin 27 move through 90 degrees (less the radius of the pin 27 and one-half the width of the spoke) before it encounters a spoke of the balance, and then move through a further distance amounting to the aforesaid angle of 270 to 330 degrees or more, before the lever 42

comes to a standstill by reason of the engagement of the contact 45 with the contact 47 in the "vibrate" position.

When the contact 45 engages contact 47, relay CR is energized again, and contacts 1, 8 open so that tube 155 ceases to conduct and the coil 121 of the relay SR is de-energized. This de-energization of relay SR leads to the starting of the mechanical and electrical operations of timing. Contacts 1, 2 reestablish a plate circuit for the tube 65, and contacts 3, 4 close to re-energize the coil of the solenoid 30 so that the winding pin 37 is retracted toward the right in Fig. 2.

With the retraction of the winding pin 27, the balance begins to turn in response to the torsion exerted by the hair spring, and assumes an oscillatory motion as indicated in Fig. 5, so that its spokes successively interrupt the light beam.

When the balance wheel BW is released, it performs its oscillatory movement, and produces the successive impulses *a*, *b*, *c*, *d*, *e*, *f* during each cycle, as stated hereinbefore. The tube 66 is conducting, and the first or *a* impulse causes the tube 65 to fire and the tube 66 to be extinguished. The tube 81 has a high voltage differential between its cathode and anode owing to the charge in condenser 89, but is prevented from firing owing to the negative charge on its grid which is not overcome by the relatively low current impulse from the tube 65, because the current flow through this tube 65 also passes through both resistors 67, 88.

The second or *b* impulse causes the tube 66 to fire and the tube 65 to be extinguished. The firing of tube 66 causes a greater current to flow through the single or common cathode resistor 68, and hence a relatively more positive potential to be placed on the grid of the tube 81, and this tube in turn will fire so that a current impulse flows by conductor 90 to the indicator Q. The condenser 89 discharges through the tube 81 and the cathode resistor 88 until its charge potential drops to a point below the critical voltage of the tube 81, the dropping occurring at a rapid rate due to the relatively low resistance of the tube 81 while conducting. Current flow through the tube 81 then ceases, and the cathode end of the conductor 90 returns to the initial potential.

The third or *c* impulse causes the tube 65 to fire and the tube 66 to be extinguished. The relatively positive potential at the grid of the tube 81 ceases, and tube 81 can now become non-conductive as the charge of condenser 89 is dissipated. Condenser 89 begins to recharge from the source A at a rate determined by the resistor 83. The balance wheel now attains the end of its forward or "tick" stroke, and reverses.

The fourth or *d* impulse causes the tube 66 to fire and the tube 65 to be extinguished. The potential across the condenser 89 has not built up to a point where it can pass through the tube 81 at the grid potential produced upon the firing of the tube 66.

The fifth or *e* impulse causes the tube 65 to fire and the tube 66 to be extinguished.

The sixth or *f* impulse causes the tube 66 to fire and the tube 65 to be extinguished. The condenser 89 has not yet received a sufficient charge for discharge through the tube 81 under 70 the grid condition now prevailing at that tube.

The balance wheel now attains the end of its rearward stroke, and reverses to start a new cycle.

At the first or *a* impulse of the new cycle, the tube 65 is fired and the tube 66 extinguished. 75

The condenser 89 is now attaining a charged condition.

At the second or *b* impulse of the new cycle, the tube 66 is fired, and the tube 65 extinguished. 5 The tube 66 acts to deliver current which establishes once more a relatively more positive potential at the grid of the tube 81, and this tube 81 now fires again owing to the combination of proper anode-cathode and grid-cathode voltages, and 10 a further impulse passes to the indicator Q.

The sequences continue so long as the system is in the determining condition.

Thus, only at the *b* impulse out of each cycle of six impulses is the tube 81 caused to fire; and 15 the assembly is selective of the impulses of the *b* type, which are produced at the moment when the balance passes its neutral axis, being thus moving at its maximum velocity in a "forward" direction or on the "tick" stroke in this illustrative example.

The alternate firing action of tubes 66 and 65 is a result of varying voltages obtained during transient conditions.

By the term "gas conduction tube" is meant 25 herein an electron discharge tube usually having a gaseous content and by which a relatively negative voltage upon a grid will inhibit the effective passage of current at a predetermined voltage between cathode and anode, while the presence 30 of a predetermined relatively more positive potential upon the grid will provoke the passage of current from cathode and anode, i. e., the firing of the tube; with a further characteristic that the established flow of current at such voltage between cathode and anode will continue substantially free from control by changes of grid potential, until the voltage between the cathode and anode has been so reduced below a certain critical 35 value that the grid can again take charge and stop the flow. This action is obtained for example in the circuit shown for tubes 65 and 66 by distributing the voltages across the condensers, resistors and tubes so that the transients appearing across the common cathode resistor 68 provides the desired effect.

With tube 66 conducting, and the source A maintaining 300 volts between conductors 69, 75, voltages during the steady state are so distributed that, for example, 45 volts appears across resistor 50 68, 15 across tube 66, and 60 volts across condenser 78 since this condenser is in parallel to the tube 66 and resistor 68. 92 volts appears across the anode resistor 79a, and 148 volts across the common anode resistor 79b. Condenser 78 55 charges up to 152 volts, as the entire 300 volts is applied to this condenser 78 except for the drop across resistor 79b. Not all of this appears across tube 65, however, as 45 volts appears on the cathode resistor 68 to reduce the voltage on tube 60 65 by that amount. The tube 65 remains non-conducting due to the biasing effect of resistor 68 until an impulse of sufficient amplitude from the input drives its grid positive. When this occurs, the tube 65 fires and passes current, and a transient condition obtains so that the minimum voltage for conduction in tube 66 is no longer present, and hence tube 66 becomes non-conducting and is extinguished. This is accomplished by maintaining constant the plate voltage supply to a conducting tube and its associated circuit elements, and increasing the voltage between the tube cathode and the reference-potential conductor 69, so that the effective voltage across the tube is lowered below that necessary 65 for conduction.

During the preceding steady state, condenser 78 has been charged to 152 volts, and the remainder of 148 volts has appeared across tube 65. At the instant tube 65 begins to conduct, the current through resistor 68 increases above .004 amp. due to the condenser 78 discharging through tube 65, resistor 67 and resistor 68. The cathodes of both tubes 65, 66 are then raised in voltage in a positive direction. The anode of tube 66 cannot rise instantaneously in relative potential, however, due to the stabilizing effect of condenser 79, as a condenser cannot charge instantaneously. Thus momentarily the tube voltage is reduced sufficiently to cause it to extinguish and become non-conductive. The extinguishing action is further assisted by a voltage drop appearing across resistor 79b due to the current surge through tube 65, part of which comes from resistors 78a and 79b. It can be seen that if tubes 66 and 65 were conductive at the same time, approximately twice the normal current would flow through resistor 79b, thus causing a very large voltage drop thereon. Tube 66 is maintained non-conducting until steady conditions are again reached as the discharge of condenser 78 causes increased voltage to appear across resistor 68, which biases the tube since it is between the cathode and the reference-potential conductor 69.

The actions of tubes 66 and 65 are identical in that as each tube is caused to fire, the other tube is extinguished; the resistor 67 is included in the cathode circuit of tube 66 in order to reduce the transient voltage caused across resistor 68 while tube 65 is conducting. In this illustrative employment, the transients provided by tube 66 and appearing between the terminal of conductor 80 and the reference-potential conductor 69 are used to activate the further tube 81. Resistor 67 reduced the transient current flowing through tube 65, thus reducing the transient voltage on resistor 68 caused by that tube.

It will be noted that the indicator Q performs its action when the tube 81 fires, which represents a succession of impulses to the indicator Q at the course of the impulses b for the successive cycles, representing the maximum velocity of movement of the balance during the "tick" stroke of each cycle.

When the indicator Q is a cathode ray tube, the time base circuit may be adjusted to the standard frequency. Then the successive impulses from the tube 81 will appear as visible deflections or "traces" of the cathode beam at an acute angle to the line established by the time-base oscillation effect. If the watch movement under test is not moving at the standard rate, these deflections will occur at successively different parts of the time-base cycle, and will have the appearance of "drifting" at a rate representing the amount of departure from the standard rate. The direction and amount of drift may be noted, and constitutes information by which the movement may be adjusted into coincidence with the standard rate.

When this determination has been made, the operator terminates the determination by moving the crank 42 in a clockwise direction (Fig. 1) from the "vibrate" position. Contact 45 is separated from contact 47, and relay CR is de-energized. Contacts 7, 8 are permitted to close, so that as permitted by the safety control, the currents in conductor 95 can again cause tubes 146, 155 to conduct current, and current through tube 155 causes energization of coil 121 of the relay SR, and the contacts of this relay are opened. 75

Contacts 1, 2 open the plate circuit of the tube 65, so that the alternate loading and firing of tubes 65 and 66 ceases. Contacts 3, 4 open the circuit through the winding solenoid 30 so that the pin 27 can move outward under the safety control into position between the spokes of the balance wheel.

The balance BW can now be removed. The crank 42 may be moved back to the "vibrate" position before or after the balance is removed: as the balance is at a standstill, this has no effect in causing movement of the balance. A new balance can be inserted as before, and the sequence of mechanical movement of the crank 42 conditions the system for a further testing operation.

Observation of the record at the indicator Q permits the operator to determine whether the balance is at the desired timing or not.

20 In the circuits shown in the figures, it will be noted that the resistors and condensers are shown conventionally at proper points for showing the entire action of the electron discharge tubes and for preventing the imposition of improper direct or straight current impulses by which improper energizations might be obtained as shown by experts in the art. The proper sizes and electrical values of these in constructional employment form no part of the invention save and except as they constitute parts of the illustrative circuits for attaining the purposes stated.

25 It is obvious that the invention is not limited to the illustrated form or purpose, but may be employed in many ways within the scope of the 30 appended claims.

I claim:

1. An apparatus for employment during rating of balance assemblies and like devices including 35 springs, comprising a frame, a first member mounted to move axially and to rock on said frame and constructed to support one end of the device when the member is in one axially-moved position, means to hold the member in its supporting position, a second member movable about 40 the axis of said first member and having means for supporting the other end of the device, gripper means carried by one of said members for engaging the spring of the device, said one member being movable about said axis to permit positioning movement of the device about its own axis, and a movable detent carried eccentrically 45 by the other of said members for selective engagement with said device for moving the same into a stressed condition and for releasing the 50 same for oscillation.

2. An apparatus for employment during rating of balance assemblies and like devices including 55 springs, comprising a frame, means on the frame for supporting one end of the device, a member 60 slidable on the frame and having an apertured end for receiving the other end of the device to support the same in position for oscillation, spring means for sliding the member into its holding position, gripper means carried by the 65 frame and movable about the axis of said device for engagement with the spring of the device and effective for moving the device into a desired neutral static position, a pin movable substantially parallel to said axis between positions in 70 which it is in the path of movement of the device and in which it is out of said path, and means on the frame to move said pin in a path about said axis whereby to place the device in a stressed condition.

3. An apparatus for rating balance assemblies

and like oscillatory devices including springs, comprising a frame, two spaced members on the frame separately rotatable about a common axis and including means for supporting the device, one of said members having means for engaging the spring and effective upon rotation to position the device at a predetermined neutral static position, the other said member having a retractable detent carried thereby for engagement in one position with the device for storing energy in the spring when the said other member is rotated, and means for controlling the position of the detent and effective for retracting the detent from said one position thereof after a predetermined amount of energy-storing movement of said other member.

4. An apparatus for rating balance assemblies and like oscillatory devices including springs, comprising a frame, two spaced members on the frame separately rotatable about a common axis and including means for supporting the device, one of said members having means for engaging the spring and effective upon rotation to position the device at a predetermined neutral static position, the other said member having a retractable detent eccentrically carried thereby and movable in a direction substantially parallel to the common axis for engagement in one position with the device for storing energy in the spring when the said other member is rotated, means for determining and indicating the rate of said device, and means for controlling said determining and indicating means and for controlling the position of said detent and effective for simultaneously retracting the detent from said one position thereof and for starting the determination of the rate of the device.

5. An apparatus for employment during rating of balance assemblies and like devices including springs, comprising a frame, means on the frame for supporting the device for free oscillation about its axis, means for engaging the spring of the device at a point offset from the axis thereof and movable about said axis for positioning the device at a predetermined neutral static position, a plunger pin for engaging within an aperture of the device, means for retracting and projecting said plunger pin, and means for translating the plunger pin about the axis of the device for storing energy within the spring.

6. An apparatus for employment during rating of balance assemblies and like devices including springs, comprising a frame, means on the frame for supporting the device for free oscillation about its axis, means for engaging the spring of the device at a point offset from the axis thereof and movable about said axis for positioning the device at a predetermined neutral static position, a plunger pin for engaging within an aperture of the device, means for retracting and projecting said plunger pin, and means for translating the plunger pin about the axis of the device for storing energy within the spring, said means including a pinion coaxial with the device, said plunger pin being supported to be translated with said pinion by a common angular movement, a toothed member for rotating said pinion and effective for moving it through an angle of more than 270 degrees, and limit stops for determining the stroke of said toothed member.

7. A rating apparatus for periodically oscillating devices comprising a support upon which

the device is placed for oscillation, a retractable detent for selectively engaging said device, means for moving said detent along the path of oscillation for storing energy in said device, a source of light and means for producing a fluctuating beam of light from said source, said device including a portion for interrupting said beam of light when the device is in a predetermined initial static position, a photo-sensitive member in the path of said beam and responsive to the fluctuations and interruptions thereof, and means connected to said member for controlling said detent so that the same can only be positioned for engagement with said device when the device has been initially statically positioned in said predetermined position.

8. A rating apparatus for watch and like balances, comprising a support upon which the device is placed for oscillation, a retractable detent for selectively engaging said balance, a rocker for moving said detent along the path of oscillation whereby to store energy in said balance, means for scanning the balance and effective for determining when a selected part of the balance is located at a neutral static position, and means responsive to said scanning and determining means for controlling the detent for preventing cooperative engagement of the detent and balance except when the balance has been initially statically positioned at the said neutral position.

9. A rating apparatus for periodically oscillating devices, comprising a support upon which the device is placed for oscillation, means for storing energy in the device whereby it may perform oscillations and including a rocker and a retractable detent carried by the rocker, contacts selectively engaged when the rocker is brought into its end limit positions, a first relay energized through said contacts when the rocker is in one limit position, a second relay, means responsive to the transits of the device in its oscillation for energizing said second relay and including means controlled by said contacts for determining the cessation of energization of the second relay when the rocker is in the other limit position, said first relay including contacts which are normally closed for establishing an energizing path for said second relay, and circuit means controlled by said second relay for determining the position of said detent so that the detent is advanced into engaging position when the device is initially placed at the neutral axis and is retracted therefrom when the device has been moved to a predetermined energy-stored position.

10. A rating apparatus for periodically oscillating devices, comprising means for supporting the device for oscillating movement, means for scanning the movement of the device, said device including elements which produce periodic impulses in the scanning means at predetermined distances of angular movements of the device, said scanning means including a part positioned and arranged so that one of said impulses during each cycle is produced at the time when the device is moving at substantially its maximum velocity, means responsive to said impulses and effective for selecting said one impulse during each cycle of oscillation, and an indicator for showing the time relationship between the successive selected impulses.

11. A rating apparatus for watch and like balances, comprising a holder in which the balance may oscillate about its axis, a member rotatable

about said axis, a detent carried for translation by said member and movable into and retractable from the path of the oscillating movement, means for moving said member whereby the detent when in one position can engage and move the balance, and means responsive to the movement of said moving means for controlling the position of said detent whereby to retract the detent from engagement with said balance after a predetermined movement of said member.

12. A rating apparatus for watch and like balances, comprising a holder in which the balance may oscillate about its axis, a member rotatable about said axis, a detent carried for translation by said member and movable into and retractable from the path of the oscillating movement, means for rocking said member through an angle greater than 270 degrees, contacts closable by said rocking means at its limits of movement, and circuit means controlled by said contacts for determining the position of said detent whereby to retract the detent from engagement with said balance after a predetermined movement of said member.

13. A timing apparatus for hair spring balances including supporting means for the balance, means including a clamping device for the hair spring and effective for initially positioning the balance at a predetermined neutral static position, means for determining the oscillatory movement of the balance, and a rockable member for moving said balance through a predetermined initial angle about its axis, and having thereon a retractable detent carried eccentrically on said member and movable toward and from the balance and effective in one position for engaging said balance, and devices connected with said detent for releasing the balance at the end of a predetermined rocking movement and also effective for energizing said movement determining means.

14. An apparatus for determining the timing of a device having a diametrically extending element of limited width which oscillates periodically through an arc greater than 180 degrees and less than 360 degrees, which comprises means responsive to selected positions of oscillation of said element for generating a group of impulses at each stroke of said element, one of said impulses being generated at the moment of substantially maximum angular velocity of the element and others at intervals therefrom representing substantially 180 degrees of angular movement before and after said one impulse, and discriminating and indicating means selectively responsive to the impulses for showing the time relationship between the said one impulses of each alternate group.

15. An apparatus for determining the timing of a device having a diametrically extending element of limited width which oscillates periodically through an arc greater than 180 degrees and less than 360 degrees, which comprises photo-electric means for scanning the oscillatory movement of said element essentially opposite the point at which the element attains its maximum angular velocity, said scanning means being effective at each stroke of said element for generating a group of electrical impulses, one of said impulses of each group being generated at the moment of substantially maximum angular velocity of the element and others at intervals therefrom representing substantially 180 degrees of angular movement before and after said one impulse, discriminating and indicating means

selectively responsive to the impulses for showing the time relationship between the said one impulses of each alternate group.

16. An apparatus for determining the time of harmonically oscillating elements having light-obscuring portions of limited width, comprising photo-electric means for scanning the element during its oscillatory movement and establishing a primary impulse when an obscuring portion has substantially its maximum angular velocity, said element oscillating during each stroke through such an arc that secondary impulses are established by said scanning means before and after said primary impulse, and discriminating and indicating means selectively actuated by the impulses for determining the time intervals between said primary impulses.

17. An apparatus for determining the timing of harmonically oscillating elements having light-obscuring portions, comprising means for supporting said element, photo-electric means for scanning the said element during oscillatory movement and for establishing electrical impulses at the passage of said light-obscuring portions, the impulses established during each stroke constituting a group, a rockable device for engaging and initially moving said element through a predetermined arc and including means for releasing said device from the element whereby the latter is freed to perform oscillatory movements, discriminating means for selectively responding to the electrical impulses, and indicating means responsive to said discriminating means for showing a selected impulse in each alternate group, and means controlled coordinately with said releasing means for initiating the action of said discriminating means concurrently with the initiation of movement of said element.

18. An apparatus for rating balance assemblies and like oscillatory devices including springs, comprising a frame, means for positioning the device for oscillatory movement and including gripper means for engaging the spring thereof, means for scanning the oscillatory movement of the device and generating thereby a group of electrical impulses for each cycle of the movement, one of said impulses being generated substantially at a point of maximum velocity of movement of the element in one direction and others at intervals of angular movement therefrom, means for discriminating between the impulses of each cycle of movement, and indicating means controlled by the discriminating means and effective for successively indicating the said one impulse of each cycle.

19. An apparatus for rating balance assemblies and like oscillatory devices including spokes and springs, comprising a frame, two spaced members on the frame separately rotatable about a common axis and including means to support the device, one of said members having means for engaging the spring and effective upon rotation to position the device at a predetermined neutral static position, the other said member having an eccentrically located plunger, said plunger in one position lying in the path of oscillatory movement of a spoke and in another position being withdrawn therefrom, means for rocking said other member whereby to wind the device through a predetermined angle to store energy in the spring, and means for retracting said plunger after completion of the winding movement.

20. An apparatus for determining the timing of a device having a plurality of angularly-spaced

radially-extending elements of limited arcuate dimensions and which device oscillates periodically through an arc greater than the angular spacing of successive radially-extending elements, which comprises means responsive to the passage of said elements during the oscillation of the device for generating a group of impulses at each cycle of said device, said means including a part so positioned and arranged that during each cycle one of said impulses is generated substantially at the moment of the maximum angular velocity of the device in one direction and other impulses at intervals from said one impulse representing angular movements corresponding to the angular spacing between the elements, and discriminating and indicating means selectively responsive to the impulses for showing the time relationship between said one impulses of each cycle.

21. An apparatus for determining the timing of a device having a plurality of angularly-spaced radially-extending elements of limited arcuate dimensions and which device oscillates periodically through an arc greater than the angular spacing of successive radially-extending elements, which comprises means responsive to the passage of said elements during the oscillation of the device for generating a group of impulses at each stroke of said device, said means including a part so positioned and arranged that during each stroke one of said impulses is generated substantially at the moment of the maximum angular velocity of the device and others at intervals from said one impulse representing angular movements corresponding to the angular spacing between the elements, and discriminating and indicating means selectively responsive to the impulses for showing the time intervals between said one impulses.

22. An apparatus for determining the timing of a structure having a diametrically extending element of a limited width which oscillates periodically through an arc greater than 180 de-

grees and less than 360 degrees in each direction and attains substantially its maximum velocity at its transits past a neutral axis, comprising means for scanning the oscillatory movement of the element and thereby generating a group of electrical impulses for each cycle of movement, each cyclic group comprising an impulse in each stroke of the cycle corresponding to the transit of said element past the neutral axis while moving at substantially maximum velocity and also comprising impulses corresponding to the transits of said element past the neutral axis during the accelerating and decelerating parts of each stroke of the cycle, means for discriminating between impulses of each group and effective for indicating the time intervals between selected maximum-velocity impulses of the successive groups.

23. A rating apparatus for hair spring balance and like oscillatory devices including a radially extending spoke, comprising a frame, means on the frame for supporting the device for oscillation, means for projecting a light beam across the path of oscillatory movement of the spoke, said beam having a dimension in the direction of said oscillatory path not essentially greater than the width of the spoke whereby the spoke can interrupt the beam, said supporting means including means for shifting the device along said path until said spoke lies in a predetermined neutral static position and across the light beam, means for winding and releasing the balance for setting the same in oscillation and including a member movable parallel to the balance axis into and out of a position for engaging the spoke, means responsive to the passage and the interruption of the light beam for indicating the rating of said device while oscillating on said supporting means, and means controlled by the said responsive means for preventing axial movement of said member into engaging position when the said member is opposite the spoke.

WALTER KOHLHAGEN.
